CLAIM

The ornamental design for a component of a device for transport of liquid, as shown and described.

DESCRIPTION

FIG. 1 is a perspective view from the front-top-right side of the component of a device for transport of liquid showing our new design;

FIG. 2 is a front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1; and,

FIG. 7 is a bottom view of the design shown in FIG. 1.
